United States Patent Office.

DAVID M. SMYTH, OF ORANGE, NEW JERSEY, ASSIGNOR TO BENJAMIN F. SMALL, OF NEW YORK CITY.

Letters Patent No. 79,924, dated July 14, 1868.

IMPROVEMENT IN LAMPS.

The Schedule referred to in these Letters Patent and making part of the same.

TO ALL WHOM IT MAY CONCERN:

Be it known that I, DAVID M. SMYTH, of Orange, in the county of Essex, and State of New Jersey, have invented a new and useful Safety-Lamp Body, and that the following is a full, clear, and exact description and specification of my said invention.

The objects of my invention are, to enable the lamp-body to retain the liquid contained in it when it is overturned, to increase its strength so that it opposes a powerful resistance to a crushing force, and to present a large surface, compared with its internal capacity, to the air, so that the air may keep it cool.

To these ends, my invention consists of a lamp-body, composed of a small tube or tubes, coiled or otherwise constructed, so as to form small cells, communicating with each other and with the burner.

My invention may be carried into effect in various forms, one of which is represented in the accompanying drawing, in which—

Figure 1 represents a side view of a safety-tube lamp-body constructed according to my invention.

Figure 2 represents a plan of the same, and

Figure 3 represents a vertical section of the same at the line $x x$ of fig. 2.

The lamp-body thus represented is formed of a metal tube, A, which is wound in a conical coil, one of its extremities being turned up in the interior of the coil to form the wick-chamber b and receive the burner, which may be screwed to the neck c at the upper end of the wick-chamber.

The wick-chamber is connected with the uppermost coil d of the tube by a small hole, e , so that, when the kerosene or other combustible fluid is poured into the wick-chamber b , the air in the coils $d d'$, &c., may escape and permit the fluid to enter.

In the lamp-body thus constructed, each coil of the tube forms a cell, containing a small quantity of the fluid, and, as all the coils communicate, the liquid can pass freely to the wick-chamber. Moreover, as each coil of tube is small in area, it opposes a powerful resistance to a crushing force, so that the lamp-body is not liable to be broken by the overturning of a railroad-car, or other accidents to which lamp-bodies are subjected in practical use. It will also be seen that the quantity of fluid that can escape from the body, in case it be upset, is extremely small, as the cells formed by the coils will retain it, and the liquid can in any event escape no faster than it can make its way through the small air-hole e . Moreover, as enough wick may be used to fill the wick-chamber b , the risk of the escape of fluid, in case of a partial or complete upset of the lamp-body, is extremely small. As the coils of tube form coils of small cross-section, surrounding a hollow space F within the coils, the air has free access to them, and carries off the heat rapidly, so that the lamp-body is not liable to overheat.

Although I prefer to construct my lamp-bodies in the form represented in the drawing, that form is not essential to the invention, as it is evident that small connected cells may be formed by coiling or bending the tube in various forms other than conical. So also it is not essential that the air-opening in the uppermost coil or cell should communicate with the wick-chamber b , as it may communicate with the external air.

I am aware that a tube more or less bent has been used in lamps to connect the burner with the body or can that constitutes the reservoir of fluid, but I do not claim such a tube-connection, as my invention has reference to the construction of the body itself.

What I claim as my invention, and desire to secure by Letters Patent, is—

The safety-lamp body, formed of a tube, and constructed substantially as hereinbefore set forth.

In testimony whereof, I have hereto set my hand, this 8th day of April, A. D. 1868.

DAVID M. SMYTH.
